UNITED STATES PATENT OFFICE

129,562

DESIGN FOR A DRESS

Margot Kops McClintock, Solesbury, Pa.

Application August 27, 1941, Serial No. 103,044

Term of patent 3½ years

To all whom it may concern:

Be it known that I, Margot Kops McClintock, a citizen of the United States, residing in Solesbury, in the county of Bucks and State of Pennsylvania, have invented a new, original, and ornamental Design for a Dress, of which the following is a specification, reference being had to the accompanying drawing, forming part thereof.

I claim:

The ornamental design for a dress, substantially as shown.

MARGOT KOPS McCLINTOCK.
